DEMOUNTABLE WINDOW SHADE
ASSEMBLYEdward C. Reilly, Chicago, Ill., assignor to The
Western Shade Cloth Company, Chicago, Ill., a
corporation of Illinois

Application March 8, 1935, Serial No. 9,966

5 Claims. (Cl. 156—23)

This invention relates to an improved demountable window shade assembly and has for one of its principal objects the provision of a novel means for positioning a pair of cooperating window shades, whereby the same with their common support may be conveniently removed from normal operating position, particularly for some temporary purpose, as, for example, the washing of windows or the like.

10 One of the important objects of the invention is the provision of a support for window shades or the like which shall be detachably positioned in a simple yet efficient manner for ready removal and shifting to another portion of the window frame when necessary or desired, and for as ready a replacement when the operation for which said removal became necessary has been completed.

15 The invention is particularly designed for use with window shades such as are commonly employed in school or similar buildings, wherein a pair of shades mounted on rollers is positioned adjacent the middle portion of a window, whereby one shade can be drawn upwardly and the other downwardly away from each other to cover any or all desired portions of the window.

20 Other and further important objects of the invention will be apparent from the disclosures in the accompanying drawing and following 25 specification.

25 The invention, in a preferred form, is illustrated in the drawing and hereinafter more fully described.

30 In the drawing:

35 Figure 1 is a vertical elevation of a window frame, showing the improved demountable window shade assembly of this invention applied thereto.

40 Figure 2 is an enlarged detail view of one end of the window shade assembly of the invention, showing parts of the shades on rollers, a portion of the light strip, and one of the holders.

45 Figure 3 is a sectional view taken on the line 3—3 of Figure 2, looking in the direction indicated by the arrows.

50 Figure 4 is a view similar to Figure 3, but showing the holder with the shade assembly removed therefrom.

55 Figure 5 is a front view of the holder of Figure 4, but illustrating the same as positioned on a different portion of a window frame, as the outside facing.

60 Figure 6 is a view showing the upper part of a window frame with the shade assembly of this invention in raised position thereon so as to be out of the way for some operation on the windows, as, for example, washing the same.

As shown in the drawing:

65 The reference numeral 10 indicates generally a window frame which has a pair of roller shades

12 and 14 applied thereto, the same being positioned on what is known as a light strip 16, this light strip being preferably of metal and extending across the medial portion of the window, and having the shades 12 and 14, with their rollers, positioned thereon as shown in more detail in Figure 2 and in such relationship that light will not pass directly through the space between the rollers.

70 As best shown in Figure 3, the light strip preferably has its upper and lower edges beaded as at 18, and either integral with or attached to each end of the light strip 16 is a forwardly extending portion 20 having bifurcated brackets 22 and 24 respectively, which brackets are provided with the usual openings and slots for the reception of the pins 26 and 28 which form part of the shade rollers. Obviously, the brackets on the other end of the light strip 16 have corresponding openings and bayonet slots for the reception of the correspondingly shaped roller pins 20 at that end.

75 A holder such as that shown in Figure 4 is fixed at each side of the window-frame 10, each holder preferably comprising a strip 34 which has its upper end bent horizontally as shown at 36 and with its lower end bent into a channel or hook shape as illustrated at 38. Integral with this strip 34 is a supporting plate element 30 which, in certain installations such as that shown in Figure 4, is for attachment to the window-frame by means of screws or the like 32 passing through suitable openings in the plate 30.

80 The strip 34 is itself provided with openings through which fastening screws 40 may pass as best shown in Figure 5, thereby adapting the same to be mounted on the forward or front face of a window-frame instead of on the inner face or side thereof as exemplified in Figure 4.

85 Latching pins 42 provided with flattened upper ends, 44, which act as handles, are provided for insertion into suitable and correspondingly shaped openings in the horizontal portions 36 of the holders. As best shown in Figure 3, when these latching pins are in position, the light strip 16 with its appurtenances is held in position in the holders. The light strip may be made in two or more telescoping sections so that it may be adjusted to varying widths of windows.

90 As will be obvious from an inspection of Figures 2 to 5 inclusive, the light strip 16, with its end fixtures 20—22—24 affixed thereto, can be readily inserted into the holders 30—34 by first removing the latching pins 42 from the openings in the elements 36 and which can be readily grasped by their upper extensions 44. When these pins are removed, the light strip with its appurtenances can be inserted into the channel portions 38, and the upper edge thereof then pushed inwardly under the projection 36 into 95

the position shown in Figure 3, whereupon the pins 42 are dropped into latching position, thereby securely fastening the shade assembly in desired relationship across the middle portion of the window and its frame.

It is preferable that the shades 12 and 14 with their supporting rollers shall have been preliminarily inserted in the supporting brackets 22 and 24 at either end of the light strip, but the rollers 10 and shades can be inserted after the light strip is in position in the holders 34. The lower shade 12 is operated by means of the usual cord 46, and the upper shade is preferably operated by a cord 48 which has its ends fastened to the edge of the shade as shown in Figure 1 and which passes over suitable pulleys or the like 50 mounted on the frame with a loop 51 extending outwardly beyond the pulleys, to which loop is attached one end of an operating cord 52. The lowermost end of this cord 52 can be fastened to a suitable hook or projection 56 mounted on the frame 10. A somewhat similar provision is made at 58 on the window sill for securing of the lower end of the cord 46.

Whenever it is desired to obtain free access to the windows as, for example, when the same are to be washed or the like, the shades are rolled onto the rollers, and the cord 46 is then wound around the rolled-up shades and the light strip as best shown in Figure 6, and temporarily secured, after which the shade assembly is removed from its supporting holders by first pulling the securing pins 42-44 and then simply tilting the entire assembly, including the light strip, forwardly, and thence upwardly out of the channel 38. After this, the cord 52 is operated to draw the entire device upwardly to the top of the frame as best shown in Figure 6, and held by tying to the projection 56, whereupon ready access can be had to the entire surface of the windows, sashes, etc., and after the washing or other operation has been completed, the device may be as conveniently replaced in the proper operating position.

It will be seen that herein is provided a window shade assembly which, while retaining all the advantages of the double shade structure, also eliminates many of the difficulties and disadvantages heretofore considered necessarily associated therewith.

In the matter of washing the windows particularly, it has been found that, in installations of this type, the shades cannot be very readily removed as individual units, and the tendency has been for window washers to attempt to clean the windows without removing the shades, resulting in spattering of dirty water or the like over the same, after which they soon become spotty and discolored, and, therefore, unsightly. Furthermore, the water on the fabric tends to shorten the life of the shades. By the use of the present invention, all necessity of removing the shades individually is eliminated, as the entire structure can be conveniently displaced and as readily replaced. The device is also particularly applicable in the event of the necessity of repairs to windows such as the replacing of glass or any other changes or repairs such as those which would involve the installing or replacement of sash locks and sash cords or the like. The invention is also useful and eliminates considerable extra work when painting is being done.

I am aware that many changes may be made and numerous details of construction varied throughout a wide range without departing from the principles of this invention, and I, therefore, do not purpose limiting the patent granted hereon otherwise than as necessitated by the prior art.

I claim as my invention:

1. A demountable window-shade assembly, comprising a pair of holders, and a support for a pair of window-shade rollers removably mounted in the holders, said support including a light strip, and brackets for a pair of shade rollers at each end of the light strip, together with latch means for locking the light strip and its roller brackets in the holders.

2. A demountable window-shade assembly, comprising a pair of holders having latch openings therein, and a support for a pair of window-shade rollers removably mounted in the holders, said support including a light strip, and brackets for a pair of shade rollers at each end of the light strip, together with latch means for locking the light strip and its roller bracket in the holders, said latch means comprising removable pins fitted through the openings in the holders.

3. A demountable window-shade assembly, comprising a pair of holders having latch openings therein, and a support for a pair of window-shade rollers removably mounted in the holders, said support including a light strip, and brackets for a pair of shade rollers at each end of the light strip, together with latch means for locking the light strip and its roller bracket in the holders, said latch means comprising removable pins fitted through the openings in the holders, said holders each comprising a flat plate, an integral strip at right-angles thereto, and a channel in the lower end of the strip.

4. A demountable window-shade assembly, comprising a pair of holders having latch openings therein, and a support for a pair of window-shade rollers removably mounted in the holders, said support including a light strip, and brackets for a pair of shade rollers mounted at each end of the light strip, together with latch means for locking the light strip and its roller bracket in the holders, said latch means comprising removable pins fitted through the openings in the holders, said holders each comprising a flat plate, an integral strip at right-angles thereto, and a channel in the lower end of the strip, together with a horizontal ledge at the upper edge of the strip.

5. A demountable window-shade assembly, comprising a pair of holders, and a support for a pair of window-shade rollers removably mounted in the holders, said support including a light strip, and brackets for a pair of shade rollers at each end of the light strip, together with latch means for locking the light strip and its roller brackets in the holders, said latch means comprising removable pins, said holders each comprising a flat plate, an integral strip at right-angles thereto, and a channel in the lower end of the strip, together with a horizontal ledge at the upper edge of the strip, said ledge provided with an opening for the passage of one of said latching pins therethrough.

EDWARD C. REILLY. 70
